US00D648249S

(12) **United States Design Patent**
Noble et al.

(10) **Patent No.:** US D648,249 S
(45) **Date of Patent:** ** Nov. 8, 2011

(54) **SADDLE FOR A SUSPENSION**

(75) Inventors: **Shawn D. Noble**, Naperville, IL (US);
Michael P. Robinson, Chicago, IL (US)

(73) Assignee: **Hendrickson USA, L.L.C.**, Itasca, IL
(US)

(**) Term: **14 Years**

(21) Appl. No.: **29/369,288**

(22) Filed: **Sep. 5, 2010**

(51) LOC (9) Cl. **12-16**

(52) U.S. Cl. **D12/159**

(57) **CLAIM**

The ornamental design for a saddle for a suspension, as shown and described.

DESCRIPTION

FIG. 1 is a front elevational view of a saddle for a suspension having the inventive design;

FIG. 2 is a rear elevational view of the saddle for a suspension shown in FIG. 1;

FIG. 3 is a right side elevational view of the saddle for a suspension shown in FIG. 1;

FIG. 4 is a left side elevational view of the saddle for a suspension shown in FIG. 1;

FIG. 5 is a top view of the saddle for a suspension shown in FIG. 1;

FIG. 6 is a bottom view of the saddle for a suspension shown in FIG. 1;

FIG. 7 is a perspective view showing the top, front, and left side of the saddle for a suspension shown in FIG. 1;

FIG. 8 is a perspective view showing the top, front, and right side of the saddle for a suspension shown in FIG. 1;

FIG. 9 is a perspective view showing the bottom, front, and left side of the saddle for a suspension shown in FIG. 1;

FIG. 10 is a perspective view showing the bottom, front, and right side of the saddle for a suspension shown in FIG. 1;

FIG. 11 is a perspective view showing the top, rear, and left side of the saddle for a suspension shown in FIG. 1;

FIG. 12 is a perspective view showing the top, rear, and right side of the saddle for a suspension shown in FIG. 1;

FIG. 13 is a perspective view showing the bottom, rear, and left side of the saddle for a suspension shown in FIG. 1; and,

FIG. 14 is a perspective view showing the bottom, rear, and right side of the saddle for a suspension shown in FIG. 1.
